CLAIM

The ornamental design for a terminal block, as shown and described.

DESCRIPTION

FIG. 1 is a bottom, front, and right side perspective view of a terminal block, showing our new design;
FIG. 2 is a bottom, rear, and right side perspective view thereof;

FIG. 3 is a bottom, rear, and left side perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The dashed broken lines in the figures show portions of the terminal block that form no part of the claimed design. The dot-dashed broken lines in the figures represent boundaries and form no part of the claimed design.

1 Claim, 7 Drawing Sheets
